UNITED STATES PATENT OFFICE.

LOUIS N. VINCENT, OF SEATTLE, WASHINGTON.

FLANGE OILER OR LUBRICATOR.

Application filed September 30, 1921. Serial No. 504,282.

To all whom it may concern:

Be it known that I, LOUIS N. VINCENT, a citizen of the United States, residing at Seattle, in the county of King, State of Washington, have invented certain new and useful Improvements in Flange Oilers or Lubricators; and I do declare the following to be a full, clear, and exact description of the invention, such as will enable others skilled in the art to which it pertains to make and use same.

My invention relates to improvements in flange lubricators, and more particularly to flange lubricators for use in lubricating or 15 oiling the flanges of the wheels of steam, electric and other cars and locomotives.

The invention consists in the several features and in the construction, combination and arrangement of such features as more 20 fully hereinafter described and claimed.

The object of the invention is to thoroughly lubricate the flanges of wheels, especially when they are traveling on the curved portions of a track, as very little lubrication 25 is required on the flanges when on a straight track.

A further object is to provide a flange lubricator which is automatically operated and caused to feed lubricant to the flanges 30 of wheels by means of the lateral or sidewise movement or play of the truck frame or engine frame from side to side and also the lateral play or movement from side to side of the wheels between the rails during their 35 travel on the track.

A further object is to provide a flange lubricator which is automatically operated and caused to supply or feed grease from the grease cups to the flange lubricating 40 means by means of the lateral or sidewise movement or play of the truck frame or engine frame from side to side and also the lateral play or movement from side to side of the wheels between the rails during 45 their travel on the track.

A further object is to dispense with all springs, weights or other devices for holding the nozzles against the flanges of the wheels, which is a great advantage, as all 50 such devices are liable to get out of order.

A further object is to provide a flange lubricator which operates automatically and requires no attention or care except the keeping of the lubricant cups well supplied with 55 lubricant.

A further object is to provide a

flange lubricator which automatically adjusts itself to the movement of the wheels in such manner that its position with relation to the wheels is always the same. 60

A still further object is to provide a flange lubricator which is simple, inexpensive and durable in construction and easy and effective in operation.

Referring to the drawings: 65

Fig. 1 is a front view, partly in section.

Fig. 2 is a central vertical section on the line 1—1— of Fig. 1.

Fig. 3 is a front view of a modified form of my invention. 70

Fig. 4 is a front view of another modified form.

Fig. 5 is a side elevation of one end of the modified form shown in Fig. 4 on an enlarged scale. 75

Fig. 6 is a side view of another modified form, and

Fig. 7 is a top plan view of the means for adjusting the connecting rod of the yokes.

In the drawings, in which similar reference characters denote similar parts throughout the several views, 1 represents the flange lubricator which comprises two lubricant containers or grease cups 2 and 3 connected or coupled together by means of a pipe 4, 80 which is adapted to be secured and supported by a suitable bracket or brackets, not shown, on a car or locomotive. 85

The lubricant containers are each made in two parts, 5 being the upper part and 6 the lower part, and connected together by means of a short vertical pipe through which the lubricant is forced, by the reciprocation of the hollow plungers, and fed from the lubricant containers to the flanges 95 of the wheels 7, and the upper part 5 of each being provided with a screw cap or closure 8, while the lower part of each is provided with a screw cap 9.

The lower surface of the pipe 4 is provided 100 with a longitudinal groove 10, and 11 is a reciprocable yoke having an upwardly projecting lug 12 which is slidable in the groove 10 and two depending curved arms 13 and 14, each having a forked lower end 15. The 105 forked ends 15 of the depending arms 13 and 14 are each mounted on and embrace a reciprocable hollow plunger or pipe 16, and each of the slidable plungers or pipes is slidably mounted in a screw threaded plug 110 18 which engages the screw threads 19 of the lower portion of the lubricant contain-

ers. A screw threaded bushing 20 is provided screwed into the screw threaded plug 18, through which the plungers or pipes 16 extend and slide and 21 is suitable packing 5 material in the recesses 22 of the screw threaded plugs 18.

The inner ends of the hollow plungers 16 are provided with screw threads 23 on which flexible rubber nozzles 24 and 25 are mounted, and the lubricant delivery end of each nozzle is made of any suitable size required to deliver the requisite amount of lubricant to the flange of the wheel.

The end of the nozzle 24 is vertical, while 15 the end of the nozzle 25 is inclined, as at 26, in order to accommodate it to the incline or shape of the flange of a wheel.

Although I have described the nozzles as being made of flexible rubber, they may be 20 made of metal or any other suitable material desired.

In the modified form of my invention shown in Fig. 3, which is designed for use when it is necessary or desired to lubricate 25 only one side of the flange of a wheel, 27 represents a single lubricant container or grease cup made in two parts, 28 being the upper part and 29 the lower part, all the several parts being made an exact counter- 30 part of the lubricant containers 2 and 3 and provided with a short piece of pipe 30 projecting laterally therefrom having a longitudinally extending slot 31.

32 is a reciprocable yoke having a projection 33 which extends upward into and through the slot 31 of pipe 30 and is provided with a roller 34 which is adapted to reciprocate freely in the pipe 30, the yoke also being provided with two depending 40 arms 35, one of which is provided with a forked end 36 similar to the forked ends of the yokes 11, and 37 is a reciprocable hollow plunger or pipe embraced and carried by the forked end 36 of the yoke 32 and secured in place by means of nuts 38.

The hollow plunger or pipe 37 is similar in every respect to the hollow plungers or pipes 16 and similarly mounted, and the end is provided with a nozzle 39 having an 50 inclined end 40.

The object of the roller 34 is to eliminate friction and reduce the wear on the end of the nozzle 39 to a minimum degree.

In the modification shown in Figs. 4 and 55 5 41 and 42 are the lubricant containers or cups connected coupled together by means of a pipe 42^a and each made in two parts, 43 being the upper part and 44 the lower part, having screws or closure caps 45 and 60 46, respectively, reciprocable yokes 47 and 48, each having a reciprocable hollow plunger or pipe 49 mounted therein.

The inner ends of each of the hollow plungers or pipes 49 being provided with a 65 nozzle 50 having a bevel wheel 51 mounted

in the outer end thereof on a short shaft 52 for the purpose of preventing the tips of the nozzle from becoming worn by the friction caused by the car wheel. The upper portions of the yokes 47 and 48 extend into the pipe 42^a through a slot 53, and 54 is a rod which is slidable in the pipe 42^a, and connects the yokes 47 and 48 together, 70 wheels 55 being provided to facilitate the sliding of the rod 54 in the pipe 42^a. 75

In the modification shown in Fig. 6 all the parts are similar to those shown in Figs. 4 and 5, except that instead of having the rod 54 for connecting the yokes a cable 55 is used which runs over small wheels 56 pivoted on short shafts 57 extending across the pipe 42^a. 80

In order to provide means whereby the nozzles may be adjusted, with relation to the wheels being lubricated, the connecting 85 rod 72 is screw threaded, as at 74, into a block 75, and by screwing the same in or out of the block the nozzles will be moved respectively toward or away from the wheels. I do not wish to limit myself to this method 90 of adjustment, as I may use any other desired means of adjusting the nozzles.

In use the flange lubricator is placed over and straddles the flange of a wheel and is adjusted, and then held in place by means of a bracket carried by the car in such position that the ends of the nozzles abut against the opposite sides of the flange of the wheel, the lubricant cups having been filled with lubricant, the reciprocating movement of 100 the yoke, produced by the lateral play or movement of the yoke, containers and the truck frame or engine frame from side to side, and also the lateral play or movement from side to side of the wheels between the 105 rails, causes the hollow plungers or pipes to be reciprocated or moved back and forth, causing the plungers to be moved inward and outward in the lower portions of the lubricant containers, and each inward movement of the plungers or pipes causes the lubricant to be continually forced through the plungers and out through the ends of the nozzles onto the flanges of the wheel, while the outward movement of the plunger 110 allows lubricant to be fed or moved downward in the lubricant containers in sufficient quantity to take the place of the lubricant which has been used, and by the continued lateral play as above described the 115 plungers are caused to reciprocate or slide back and forth and the extent of movement of the plungers is regulated by the extent of lateral play as above described, first one plunger being slid against the flange of the 120 wheel and then the other.

The continuous turning or rotating of the wheel causes the lubricant fed to the flanges to be spread all around the flange.

The constant jarring of the car results in 130

the continual packing of the lubricant in the containers.

As the lubrication of the flanges is required mostly on curves, when the wheel takes the curve it will cause the flange lubricator to force the lubricant onto the flange and in turning the curve either to the right or to the left, as the case may be, the side of the curved track where the lubricant is needed will be the side lubricated, and when running on a straight track there will be sufficient lateral motion or play to cause the lubricator to continually supply a sufficient amount of lubricant to the flanges.

I do not wish to be understood as limiting myself to the specific details of construction and arrangement as herein described and illustrated, as it is manifest that variations and modifications may be made in the features of construction and arrangement in the adaptation of the device to various conditions of use without departing from the spirit and scope of my invention and improvements. I, therefore, reserve the right to all such variations and modifications as properly fall within the scope of my invention and the terms of the following claims.

What I claim is:

1. A flange lubricator for wheels provided with longitudinally reciprocable hollow plungers through which lubricant is forced by the reciprocation of said plungers and fed to the flanges of the wheels, said plungers being reciprocated by the lateral movement or play of the truck frame or engine frame from side to side and also by the lateral play or movement from side to side of the wheels.

2. A flange lubricator for wheels provided with reciprocable hollow plungers through which lubricant is forced by the reciprocation of said plungers and fed to the flanges of the wheels, said reciprocable plungers reciprocated by the lateral movement or play of the truck frame or engine frame from side to side and also by the lateral play or movement from side to side of the wheels.

3. A flange lubricator for wheels provided with lubricant receptacles, reciprocable hollow plungers mounted in said receptacles through which the lubricant is forced and fed from said receptacles to the flanges of the wheels by the reciprocable movement of the plungers in the receptacles.

4. A flange lubricator for wheels provided with lubricant receptacles, reciprocable hollow plungers or pipes slidable in said receptacles, through which the lubricant is forced and fed from the lubricant receptacles to the flanges of the wheels, and a slidable yoke connected to said hollow plungers or pipes, said hollow plungers adapted to contact with the flanges of a wheel and be reciprocated by the lateral movement or play of the truck frame or engine frame from side

to side and also by the lateral play or movement from side to side of the wheels.

5. A flange lubricator for wheels provided with lubricant receptacles, means for connecting said receptacles having a groove, hollow plungers or pipes mounted and slideable in said receptacles, and a yoke connected to said hollow plungers or pipes and having a lug slideable in the groove of the connecting means of the said receptacles, 70 said plungers and yoke being reciprocated by the lateral movement or play of the truck frame or engine frame from side to side and also by the lateral play or movement from side to side of the wheels.

6. A flange lubricator for wheels provided with lubricant receptacles having upper and lower portions, means for securing said portions together, a pipe connecting the upper portions of said lubricant receptacles having a groove, a yoke having a lug seated and slideable in said pipe, hollow plungers or pipes connected to said yoke and mounted and slideable in the lower portions of said receptacles, said yoke and plungers being 85 reciprocated by the lateral movement or play of the truck frame or engine frame from side to side and also by the lateral play or movement from side to side of the wheels.

7. A flange lubricator for wheels provided with a lubricant receptacle provided with a lateral extension having a slot, a yoke provided with a lug extending through said slot and provided with anti-friction means, a hollow plunger or pipe with a nozzle, said plunger carried by said yoke and slideable in said lubricant receptacle, said plunger being reciprocated by the lateral movement or play of the truck frame or engine frame from side to side and also by the lateral play or movement from side to side of the wheels.

8. A flange lubricator for wheels provided with lubricant receptacles, longitudinally reciprocable hollow plungers or pipes through which the lubricant is forced and fed from the lubricant receptacles to the flanges of the wheels, said plungers mounted and slideable in said lubricant receptacles, a yoke provided with depending arms connected to said hollow plungers, adjustable nozzles on the hollow plungers, means for slidably supporting said yoke, said yoke and plungers reciprocated by the lateral movement or play of the truck frame or engine 100 frame from side to side and also by the lateral play or movement from side to side of the wheels.

9. A flange lubricator for wheels provided with lubricant receptacles, means for connecting said receptacles, longitudinally reciprocable hollow plungers or pipes through which the lubricant is forced, by the reciprocation of said plungers in the said lubricant receptacles, a yoke slideable in the said con- 125

necting means of the said lubricant receptacles and provided with arms with which said plungers are connected, said yoke and plungers adapted to be reciprocated by the 5 lateral movement or play of the truck frame and also by the lateral play or movement of the wheels.

10. A flange lubricator for wheels provided with lubricant receptacles, recipro-
10 cable plungers mounted in said receptacles

and each having an unrestricted passage therethrough through which the lubricant is forced and fed from the said lubricant receptacles to the flanges of the wheels by the reciprocable movement of the plungers in 15 the receptacles.

In testimony whereof, I have affixed my signature.

LOUIS N. VINCENT.
